UNITED STATES PATENT OFFICE.

SYLVESTER H. DEIHL, OF ALTOONA, PENNSYLVANIA.

RAILWAY-JOINT.

SPECIFICATION forming part of Letters Patent No. 704,817, dated July 15, 1902.

Application filed January 7, 1902. Serial No. 88,709. (No model.)

To all whom it may concern:

Be it known that I, SYLVESTER H. DEIHL, a citizen of the United States, residing at Altoona, in the county of Blair, State of Pennsylvania, have invented certain new and useful Improvements in Railway-Joints; and I do hereby declare the following to be a full, clear, and exact description of the invention, such as will enable others skilled in the art to 5 which it appertains to make and use the same.

This invention relates to railways; and it has for its object to provide a joint for holding the meeting ends of the rails in such manner that disjoining of the ends of the rails 15 will be prevented by reason of the secure fastening means, a further object of the invention being to so construct the base of the joint that should the clamping means become loose the rails will yet be held against 20 placement.

Other objects and advantages of the invention will be understood from the following description.

In the drawings forming a portion of this 25 specification, and in which like numerals of reference indicate similar parts in the several views, Figure 1 is a perspective view showing the meeting ends of two rails equipped with and held in a joint constructed in accordance with the present invention. Fig. 30 2 is a transverse section through a rail and the joint and showing the clamping means. Fig. 3 is a perspective view showing the main member or base of the modified form of the 35 invention. Fig. 4 is a perspective view of the fish-plate.

Referring now to the drawings, in this embodiment the invention consists of the main member, including a base 10, at one edge of 40 which is the upwardly and inwardly directed flange 11, having the upwardly-directed portion 12 at its inner end, which is adapted to rest against the face of the web 13 of a rail, while the lower portion of the flange rests 45 against the upper face of the base-flange 14, which latter fits between the flange and the base. The inner face of the portion 12 has an edge flange 15, which directly engages the web of the rail, as shown. At the opposite 50 side edge of the base 10 is the vertical flange 16, for a purpose to be presently explained. In connection with the base is employed a

fish-plate 17, including the lower portion 18 and the upper portion 19, lying at an obtuse angle to each other, the lower portion being 55 adapted to fit snugly against the upper face of the base-flange of the rail, while the upper portion rests against the face of the web of the rail.

Through the base 10 is formed a perforation 60 20, which registers with a notch in the lower portion of the flange, and through this perforation and notch is passed a bolt 21 in an upward direction, and this bolt is engaged through a perforation 22 in a wedge-block 23, 65 which is formed to fit against the faces of the fish-plate and the inner face of the flange 16, said plate and flange diverging upwardly, so that when the block is drawn downwardly by means of the nut 25, engaged with the bolt, 70 the fish-plate will be forced against the rail to force it in turn against the opposite flange of the base and to hold it securely.

It is of course understood that the ends of two rails are disposed upon the base so that 75 the fish-plate engages both rails and holds them securely to the base. It will be noted, furthermore, that the upper portion of the fish-plate has a flange 27, which directly engages the web of the rail shown. A lip 30 80 is formed upon the upper face of the base 10 and adjacent to the flange 16, so that the meeting ends of two rails may be engaged therebelow, as shown, and will be held by said lip, in connection with the opposite 85 flange 11, against upward movement should the wedge-block become loose. The fish-plate 17 has a notch 36 in its lower portion, so that it may be fitted over the lip.

In practice modifications of the invention 90 may be made, and any suitable materials and proportions may be used for the various parts without departing from the spirit of the invention.

What is claimed is—
95
A device of the class described comprising a base having flanges at its side edges, one of said flanges including a lower portion at an acute angle to the base and an upper portion at a right angle to the base, a lip on the base 100 adjacent to the opposite flange, a plate including a lower portion adapted to lie flush with the under face of the lip and an upper portion for engagement with the web of a rail,

said lower portion having a recess to receive the lip, a wedge-block adapted to engage between the plate and the adjacent flange of the base, and a bolt passed through the base 5 and block and having a nut for engagement with the block to draw it downwardly, between the plate and flange.

In testimony whereof I affix my signature in presence of two witnesses.

SYLVESTER H. DEIHL.
